UNITED STATES PATENT OFFICE

2,650,445

CRUCIFIX FOR ROSARIES, NECK CHAINS,
OR THE LIKEHorace Randall, Pawtucket, R. I., assignor to The
H. M. H. Co., a corporation of South Dakota

Application April 29, 1950, Serial No. 159,006

2 Claims. (Cl. 41—10)

1

This invention relates to a crucifix for use on a rosary or neck chain.

Crucifixes which are used for personal wear and worn on a rosary or neck chain usually consist of a cross with a corpus secured thereto, all of which is metal and often is formed of the more precious metals with no halo present.

One of the objects of this invention is to provide a halo for the corpus.

Another object of this invention is to provide a halo which may be easily assembled with the crucifix.

Another object of this invention is to provide a halo which may be formed of a different color to contrast with the remainder of the crucifix, or of the same color if desired.

Another object of this invention is to provide a halo which may be of a separate part and assembled with a crucifix which is already formed without materially changing the crucifix.

With these and other objects in view, the invention consists of certain novel features of construction, as will be more fully described and particularly pointed out in the appended claims.

In the accompanying drawings:

Figure 1 is a front elevation of the crucifix with the halo in place;

Figure 2 is a side view thereof;

Figure 3 is a perspective view looking at the back side of the corpus;

Figure 4 is an elevation of the cross;

Figure 5 is a perspective view of the halo;

Figure 6 is an exploded view of the corpus, halo, and cross in separate position but in their relative positions for attachment together;

Figure 7 is a section on line 7—7 of Figure 2 with the corpus omitted; and

Figure 8 is a sectional view on line 8—8 of Figure 2.

In proceeding with this invention, I cut from a separate piece of material an elongated body member with an opening at its lower end for assembly on the pin which secures the lower part of the corpus to the cross, and provide at the upper end an arcuate portion to serve as a halo back of the head of the corpus. Rearwardly extending lugs are formed to extend along the opposite edges of the cross so as to prevent this member from movement when assembled on the cross. Thus, the halo member is assembled by positioning it upon the lower pin of the corpus and then placing both the corpus and halo on the cross and riveting the corpus in place in a usual manner.

With reference to the drawings, 10 designates

5

a cross having laterally extending limbs 11, 11 and a vertically extending lower limb 12. At the upper end of this cross there is an opening 13 for supporting it on a chain. A hole 14 is provided in the lower limb 12 and holes 15 are provided in the lateral limbs 11 of this cross.

10

The corpus is designated generally 16, shown by itself in Figure 3, and comprises the sculpturing of a representation of Christ having a body 17 and outstretched arms 18, 18. At the lower end of the body there are the feet 19. The outstretched arms 18, 18 are of a size to have the hands cover the openings 15 in the limbs 11 of the cross, while the body is of such extent that the feet 19 cover the opening 14 in the lower limb 12 of the cross. Pins 20 are fastened to the arms and extend through openings 15 to secure the arms of the corpus to the cross, while pin 21 is fastened to the feet 19 and extends through opening 14 in the lower limb 12 of the cross to secure this portion of the corpus to the cross.

15

The halo member which has not heretofore been provided in ornaments of this character is designated generally 22 and comprises an elongated body portion 23 with an opening 24 at its lower end and a circular halo 25 at its upper end which is pierced as at 26 so as to form a cross 27 within a circular margin. Lugs 28 extend rearwardly from either side of the longitudinal member 23 about midway of its length.

20

In assembly, the halo member 22 is positioned so that the pin 21 will extend through the opening 24 while the circular part 25 is located in back of the head 30. The corpus and halo thus assembled are positioned so that the pins 21 extend through the opening 14 and the pins 20 extend through the openings 15. These pins are then riveted over as indicated at 31 in Figure 8, while the lugs 28 extend along either side and closely fit the limb 12 of the cross (see Figure 7). This provides for a simple assembly of the parts with but little more to do for the provision of a halo than is necessary for the assembly of the parts without the halo.

25

The halo 22 being formed of a separate piece of metal may be made from any color metal either in a contrasting finish or a similar finish which should enhance the crucifix in appearance.

I claim:

30

1. An ornament comprising a cross, a corpus with outstretched arms, pins one of which extends from the lower part of the corpus through

35

the cross securing the corpus to the cross and

2

a member between the two through which the pin through the lower part of the corpus passes said member extending lengthwise of the corpus upwardly to a point above the head of the corpus with a curved upper end located back of the head of the corpus to serve as a halo, and lugs on the member at a point above the said pin extending rearwardly on either side of the cross to prevent swinging of the member about the pin.

5

2. An ornament as in claim 1 wherein the pins pass through the arms and feet of the corpus and the member is mounted on the pin fastened to the feet.

HORACE RANDALL.
